UNITED STATES PATENT OFFICE.

FREDRICK SIEVERN, OF MCKEESPORT, PENNSYLVANIA.

WELL-CAPPING DEVICE.

Application filed April 12, 1920. Serial No. 373,453.

To all whom it may concern:

Be it known that I, FREDRICK SIEVERN, a citizen of the United States, and resident of McKeesport, in the county of Allegheny 5 and State of Pennsylvania, have invented a new and useful Improvement in Well-Capping Devices; and I do hereby declare the following to be a full, clear, and exact description thereof.

10 My invention relates to apparatus for capping oil and gas wells, and it has for its object to provide a simple and effective device whereby, when a drilled well begins to flow, it may be quickly and easily brought under 15 control.

When an oil or gas well is brought in, that is to say, when the drill penetrates the sand where the oil or gas is held under high pressure, considerable difficulty is experienced in controlling the flow from the mouth of the well. This is especially difficult in the case of gas wells which often, when first brought in, flow at the rate of many millions 20 of cubic feet per day, and therefore issue from the mouth of the well at such a high velocity that ordinary capping means are not sufficient. Also, such wells often catch fire and may burn for many days before the flames are extinguished and the well brought 25 under control.

My present invention aims to avoid the difficulties mentioned above by means of a device composed of two main parts, one of which is attached to the upper section of 30 the well casing during the drilling operation, while the second member carries a valve which is moved over the mouth of the well and securely fastened in place without interrupting the flow of gas or oil, the flow 35 being then stopped by simply closing the valve.

One effective form of my device is illustrated in the accompanying drawing, in which Fig. 1 is a plan view of the assembled device; Fig. 2 is a longitudinal vertical sectional view taken centrally of the device shown in Fig. 1; and Fig. 3 is an end elevational view of the same device.

As shown in the drawing, the device consists of a rectangular base plate 1 provided 40 with a circular opening 2 which is screw-threaded for attachment to the upper end of a well casing 3. The plate 1 has a channel or vent opening 4 communicating with the 45 circular opening 2, and is also provided with a flange 5 that extends around three sides

of the plate 1 and is undercut as shown at 6 to provide a dove-tailed seat for a cover plate 7. The sides and one end of the plate 7 are beveled as shown at 8 to fit in the 60 dove-tailed seat provided by the flange 5, and the plate 7 is also provided with a threaded opening 9 for receiving a globe-valve 10 and with two smaller openings 11 which register with similar openings 12 in 65 the plate 1 when the plate 7 is slid into the plate 1 when the plate 7 is slid into position on the plate 1, as shown on the drawing. Bolts 13 are passed through the registering openings 11 and 12 in the base-plate and the cover-plate and are fastened 70 in place by means of nuts 14.

While the well is being drilled, the base-plate 1 is secured to the top of the upper section of the well casing, and does not obstruct the drilling operation in any way. As 75 the casing is lengthened by adding new sections, the plate is removed from the old top section and attached to the new top section. When the gas or oil begins to flow from the well, and it is desired to bring the flow 80 under control, the plate 7 carrying the valve 10 is slid into its seat on the base plate 1 which may be accomplished even though the well is flowing under high pressure, because the vent opening 4 maintains continuous free 85 communication between the casing 3 and the opening 9 in the cover plate 7 while the cover plate is being slid into position. The valve 10 is, of course, open at this time and the gas or oil therefore escapes freely. 90 When the plate 7 is fully seated on the base plate 1, it is secured in place by means of the bolts 13 and the nuts 14, whereupon the flow from the well may be shut off by closing the valve 10. This valve may be the permanent control-valve for the well, and may be 95 of any usual or desired construction.

It is a special advantage of my present invention that the well is capped without interrupting its flow. Previous devices for 100 bringing high-pressure wells under control have been difficult to apply, because they have involved shutting off the flow from the well at least momentarily and thereby working against the full pressure of the well. According to my present invention, the cut-off valve is securely applied to the well casing, but the flow from the well is never interrupted until after the valve is permanently fastened in place.

While I have herein shown and described 110 an embodiment of my invention which I

have found to be effective and which I now prefer to employ, it will be evident that various changes in the forms and arrangement of parts may be made without departing from my invention, and I therefore desire that no limitations be imposed upon my invention, except such as are indicated in the appended claims.

What I claim is:

1. A well-capping device comprising a cut-off valve and means movable across the mouth of a well for securing the said valve thereto, the said means including a continuously open channel for permitting the free flow of fluid from the well while the said valve is being applied.

2. A well-capping device comprising a member adapted to be attached to the well casing during drilling, a cut-off valve and a member carrying said valve and adapted to be moved across the opening of the said well and to be held in place by the said first-named member.

3. A well-capping device comprising a member adapted to be attached to the well casing during drilling and provided with a seat, a second member, slidably received in said seat, a valve carried by said second member and means for permitting uninterrupted flow of fluid through the said device while the said second member is being slid into the said seat.

4. A well-capping device comprising a base plate adapted to be attached to the well casing during drilling, the said plate being provided with a seat for receiving a second plate, and also being provided with a vent

opening, a cover plate adapted to be slid into the said seat in the said base plate, and means for securing the said plates together. 40

5. A well-capping device comprising a base plate having a screw-threaded opening for attachment to the upper end of a well casing, the said base plate being also provided with a vent opening communicating 45 with the said screw threaded opening, a flange formed on the said base plate and having undercut sides forming a dove-tailed seat, a second plate adapted to fit within the said seat and having a screw-threaded opening 50 for receiving a control valve, and means for securing the said plates together.

6. A well-capping device comprising a base plate having a screw threaded opening for attachment to the upper end of a well-casing, the said base plate being also provided with an elongated depression or vent opening communicating with the said screw-threaded opening, a flange formed on the said base plate, and undercut to provide a 55 dove-tailed seat, a cover plate adapted to be slid into the said seat and having a screw threaded opening communicating with the said vent opening while the said cover plate is being slid into position, the said base 60 plate and cover plate being provided with registering openings for receiving fastening means.

In testimony whereof I, the said FREDRICK SIEVERN, have hereunto set my hand.
FREDRICK SIEVERN.
